UNITED STATES PATENT OFFICE.

KENNETH DAVIS, OF ST. BENEDICT, PENNSYLVANIA, ASSIGNOR TO REMBRANDT PEALE, OF NEW YORK, N. Y.

MINING MACHINE.

Application filed September 11, 1917. Serial No. 190,731.

To all whom it may concern:

Be it known that I, KENNETH DAVIS, a citizen of the United States, residing at St. Benedict, in the county of Cambria and 5 State of Pennsylvania, have invented certain new and useful Improvements in Mining Machines, of which the following is a specification.

The invention relates to mining machines, 10 and in certain aspects thereof more especially to mining machines which complete the displacement or dislodgment of the coal or other mineral from the vein or seam; the invention including also cooperating means 15 for loading the dislodged mineral into mine cars.

Further objects and advantages of the invention will be set forth in part hereinafter and in part will be obvious herefrom, such 20 objects and advantages being attained through the instrumentalities and combinations pointed out in the appended claims.

The invention consists in the novel parts, constructions, arrangements, combinations 25 and improvements herein shown and described.

The accompanying drawings, referred to herein and constituting a part hereof, illustrate one embodiment of the invention, and 30 together with the description serve to explain the principles thereof.

Of the drawings:

Figs. 1 and 2, taken together with Fig. 1 at the left and Fig. 2 at the right, constitute 35 an elevation of a machine embodying the invention;

Figs. 3 and 4, taken together in like manner, with Fig. 3 at the left and Fig. 4 at the right, constitute jointly a top plan corresponding to Figs. 1 and 2;

Fig. 3^a is a view of a detail.

Fig. 5 is a vertical, transverse section taken on the line A—B of Figs. 1 and 2, the different parts of the section being taken on 45 different vertical planes for the sake of simplicity and clearness (the central part being through the pivot pin 72);

Fig. 6 is an end elevation looking at Figs. 2 and 4 from the right;

Fig. 7 is a top plan (largely in outline 50 only) of the machine and conveyor showing one position when loading coal into a mine car;

Fig. 8 is a side elevation corresponding to Fig. 7 but omitting the machine;

55

Fig. 9 is a fragmentary sectional elevation of the drive between the motor and the platform carrying the cutting ring;

Fig. 10 is a vertical section (developed on a plane) through the swing sections of the 60 conveyor which are adjacent to the cutting ring;

Fig. 11 is a horizontal section through the parts shown in Fig. 10;

Fig. 12 is a fragmentary elevation of a 65 portion of the conveyor; and

Fig. 13 is a transverse vertical section on line C—D of Fig. 12;

Referring more particularly to the accompanying drawings, illustrating by way of example one embodiment of the invention, means are provided for removing the coal, or other mineral by the direct operation of the machine (that is without blasting or other subsequent operations) and without 75

the necessity of traveling the machine while removing a portion or section of coal from the vein. By my invention the mineral removing mechanism is rotated or otherwise 80 operated to cut the mineral and the mechanism is at the same time automatically advanced through the mineral as the cutting is effected to keep it in effective contact with the work, these mechanisms being simultaneously driven by the motive power, which 85

also returns the mechanism for a new cut.

In connection with the foregoing, means are provided whereby the mineral is sequentially and automatically conveyed away from the mechanism which dislodges it from 90 the seam, and is automatically conveyed to and loaded into the mine cars.

Means are provided for progressing the entire machine without tracks and for also holding it in stationary position, and in each 95 case entirely independently of the tracks for the mine cars, and without the necessity of laying tracks for this machine. Such means provide also for the free and facile handling of the machine in any direction over the 100 mine bottom, as desired, the machine maintaining its position without braces or stays of any kind while removing the mineral.

Other features and aspects of the invention will be set forth hereinafter, or will be 105 obvious from the description of the mecha-

nism, the same cooperating in the present embodiment with the various features and means already referred to.

Referring more particularly to the construction illustrated in the accompanying drawings, a rotating endless cutting device is supported upon and driven by the machine, the machine at the same time positively progressing the rotating cutting device 10 through the coal, ore or other mineral, such progressing movement of the rotating cutting device being preferably arcuate and reciprocatory; the backward reciprocation positioning the cutting device for the next 15 succeeding cut.

As embodied, a ring 1 is provided in its front, flat edge with teeth 2, which teeth are preferably arranged in various positions so as to cut adequate clearance space 20 about the ring as it advances through the mineral, the displaced material passing on within the ring. As embodied, teeth 2^a are set in alinement with the ring 1 to cut the mineral immediately ahead of the ring. 25 These teeth are provided with bevel cutting faces formed on the head thereof, from which head extends a shank. This shank fits into a recess in the flat or front edge of the ring 1. The edge of the ring 1 is recessed or stepped, as shown at 3 in Figs. 1 30 and 3, the tooth-receiving recesses being formed in the leading or projecting portions of the steps in the edge of the ring. Fastening means for the respective teeth are provided, being preferably in the form of clamping screws 4, located in the recessed portions of the edge of ring 1, and engaging the shanks of the teeth 2 to hold them in position, as shown in Fig. 1.

40 The teeth 2^b are set sidewise and slantingly and projecting outwardly from the ring 1, so as to cut outwardly or on a greater diameter than the ring and thereby provide clearance on that side thereof. The cutting teeth 2^c are inserted in a similar manner, but project inwardly, or on the opposite side of the ring 1 from the teeth 2^b, and cut on a less diameter than the ring, thereby providing clearance in the cut on the inside of the 45 ring. These teeth are likewise held by the clamping screws 4.

The ring 1 is rotatively mounted upon a support carried from the machine, and as shown, ring 1 has fastened to its back or inner face a ring 6 (Fig. 3) which ring projects inwardly into a recess in a stationary ring 7, the ring 7 extending within and closely fitting the ring 1. The ring 1 is shouldered at its forward end, in turn closely fitting the flat edge of ring 7, as shown at 8, Fig. 3, whereby the inner surfaces of the rings 1 and 7 are of the same diameter and present a smooth and uniform inner surface. Wear rings 9 and 10 are provided 65 between the surfaces of rings 1 and 7, if de-

sired, same being replaceable and taking up the wear therebetween.

The stationary ring 7 is nested into a circular supporting frame 11, fitting thereabout, as shown in Fig. 3. The outer surface of frame 11 has the same curvature as the outer part of member 170, to be described later. The circular frame 11 is connected to, or integral with, a supporting frame 12. The frame 12 extends backwardly on one side, as shown at 13, terminating in an outwardly extending guiding flange 14, which flange is enclosed within guiding members 15 formed on the machine frame. The frame member 12 likewise extends in the opposite direction, that is on the other side (Fig. 3) and terminates in a flange 16, which flange is enclosed within a vertical guideway 17, likewise formed on the machine frame. In the vertically-disposed guiding supports and connections just described, the ring 1 is movable up and down, that is, in its own plane or transversely to its own axis, to adapt the machine to veins or seams of different heights, or to operate upon different parts of the seam. Mechanism is provided for so raising and lowering the cutting ring which will be later described.

Means are provided for rotating the cutting ring 1 at any point of elevation or depression and while it is simultaneously automatically driven forward through the mineral by the motor, and in the embodied form thereof, there are provided in the external periphery of the ring 1 sprocket holes 20, with which intermesh teeth on a sprocket wheel 21. A reinforcing or backing support 19 may be used to prevent any possible springing of the cutting ring away from its driving sprocket. The sprocket wheel 21 is mounted on a stub shaft 23 journaled in a bearing 24 mounted upon the slidable frame 12, which supports the cutting ring. Sprocket wheel 21 has driving connections suitable for the movement of the frame 12, and as embodied, a gear wheel 25 is fixed on the shaft 23 of the sprocket wheel. Meshing with the gear wheel 25 is a floating idler pinion 26, which pinion is carried between and journaled in two parallel frames 27 and 28. The frames 27 and 28 at one end are pivoted on the shaft 23. At the other end frames 27 and 28 are pivotally connected to similar frames 29 and 30, by reason of all four frames serving as journals for a second idler pinion 31, which meshes with the pinion 26 and also a gear wheel 32. Gear wheel 32 is mounted loosely on a driven shaft 33, arranged transversely of and journaled upon the machine (Figs. 1 and 3). The frames 29 and 30 are supported at their other end upon the shaft 33. The gearing just described serves as a drive for the cutting ring 1, through sprocket wheel 21, notwithstanding the vertical

changes in the position of the cutting ring.

Fixed to the gear 32 and loose therewith on shaft 33 is a clutch member 35. A cooperating clutch member 36 is fast on shaft 33, the operation of the clutch 35, 36 controlling the rotation of the cutting ring 1. Shaft 33 is driven in a suitable manner, and as embodied, the shaft is provided at its other end (Fig. 3) with a gear 37. Meshing with the gear 37 is an idler 38, which in turn is driven by a pinion 39, on the shaft of a motor within the casing 40. This clutch and the others shown in the machine, will be operated by hand levers, or other suitable devices, same being omitted from the drawings for the sake of clearness.

Referring to the means for raising and lowering the cutting ring, previously referred to, it will be recalled that the frame 12, by means of the guiding flanges 14 and 16 may move up and down vertically in the guides 15 and 17 on the machine frame. A vertically disposed shaft 50 is supported in the lower part of the frame 12 (Fig. 1) so as to be rotatable while being held longitudinally in respect to the frame. Said mounting as embodied comprises a collared hub 51 at the lower end of the shaft 50, the collared hub fitting into the frame 12. The shaft 50 is screw threaded, as shown at 52 and carries an internally screw-threaded beveled gear 53. Beveled gear 53 is rotatably mounted, as by a collared hub 54, journaled on the machine frame. Meshing with the gear 53 is a beveled gear 55, which gear is mounted on a horizontally disposed shaft 56. The shaft 56 is journalled in a bearing 57 on the machine frame. At the opposite end thereof, shaft 56 carries a beveled gear 58. Meshing with the gear 58 are two beveled gears 59 and 60, which are loose on shaft 33, and are provided, respectively, with clutch members 61 and 62. Between the clutch members 61 and 62 is a common clutch member 63 rotating with, but slideable along, shaft 33. Clutch member 63 is held in a central or disengaging position, or can be thrown into engagement with the clutch member 61 or with clutch member 62, to rotate shaft 56 in either direction as desired. When shaft 56 is rotated in one direction or the other, it rotates beveled gear 53 in the corresponding direction. By reason of gear 53 being held in fixed position upon the machine frame, and being in screw-threaded engagement with shaft 50, and the mounting of the shaft upon the frame 12, the cutting ring 1 is raised or lowered, as desired, by the operation of the clutch member 63, as just described.

Means are provided for controlling the limit of elevation and depression of the cutting ring and for preventing jamming of

the mechanism. As embodied, the projections on the clutch members 61, 62 and 63, are preferably cut at a greater angle than the angle of repose as shown in Fig. 3^a, and thereby the operator must hold the clutch in 70 by hand while the cutting ring is being raised or lowered, and when the operator releases the clutch, or on the ring reaching the limit of its travel, the clutch 63 will be thrown automatically to neutral position 75 without jamming the mechanism.

Means are provided for driving the cutting ring 1 forward while it is being rotated, and preferably for driving the ring in an arcuate path about a center. In the 80 embodied form of such means, the frame of the machine which supports the mechanism already described is fixed to a base-plate 70. The plate 70 is supported upon a bed 71 by means of a pivot or post 72. A 85 retaining cap 73, of greater diameter than the post 72, is fixed to the top of the post in a suitable manner, as by bolts 74, and serves to hold the base plate 70 and its sup- 90 ported mechanism in position upon the bed 71, while permitting the mechanism to ro-tate about the post 72.

In the embodied form of means for driv-ing the cutting ring 1 in its forward arcuate path (it in the meantime being rotated on its supporting frame by the mechanism already described), a yielding action is pro- 95 vided, as the cutting ring may encounter hard places in the mineral which might break or otherwise injure the machine if the drive were rigid. Such embodied form comprises a pinion 76 fixed on the oppo-site end of the motor shaft from the pinion 39. Pinion 76 meshes with a gear 77 carried on a stub shaft 78. Fixed also on 100 shaft 78 is a bevel gear 79, and meshing therewith is a bevel gear 80. The gear 80 is fixed upon a vertically disposed shaft 81, journaled in supporting brackets 82, 83 and 84, mounted upon the motor casing and up- 105 on the machine frame. Fixed on shaft 81 is an arm 88, the outer end of the arm carry-ing a stub shaft 89. Loose on shaft 89 is a double pinion 90, 91. Meshing with the pinion 90 is a gear wheel 86, and fixed to, 110 or integral therewith, is a sleeve 86^a. Sleeve 86^a and gear 86 are loose on shaft 81. Fixed to sleeve 86^a is a bevel gear 95, which meshes with a bevel gear 96, loosely mounted upon a shaft 97 arranged transversely of the ma- 115 chine frame (Figs. 3 and 5). Fixed also to sleeve 86^a is a bevel gear 98, which meshes with a bevel gear 99, the latter being like- 120 wise loosely mounted on shaft 97.

Bevel gear 96 is provided with a clutch 125 member 100, and bevel gear 99 is provided with a clutch member 101. Cooperating with the clutch members 100 and 101 is a clutch member 102, which is interposed therebetween and is mounted upon the shaft 130

97 to rotate therewith but being slidable therealong to engage either clutch member 100 or 101. The shaft 97 is journaled in bearings 104 and 105 mounted upon the 5 bed plate 70, which bed plate at this end thereof is of arcuate form and concentric with the post 72. Fixed to the shaft 97 is a worm gear 106, which intermeshes with an arcuate series of gear teeth 107 formed 10 on a plate 108 bolted to the bed 71.

Pinion 91 meshes with a gear wheel 87, which wheel is fixed to a band-controlled 15 brake wheel 92, both being loose on sleeve 86^a. The periphery 93 of wheel 92 will have a band and lever brake applied thereto in the usual manner, same being omitted for the sake of clearness. Gear 98 will be used to progress the ring along its path during the cutting of the mineral and gear 95 20 during the idle return movement to position for a new bite on the vein. When there is no pressure on brake wheel 92, and gear 86 offers resistance, pinion 91, will rotate gear 87 idly. When braking pressure is applied 25 to wheel 92 and gear 87 is retarded or stopped, pinion 90 will rotate gear 86 and swing platform 70 about its pivot 72 in the direction determined by clutch member 102. The pressure on brake wheel 92 will be so 30 regulated as to produce the above action, and yet allow slippage or yielding whenever the cutting ring strikes an unusually hard spot in the vein.

The machine is adapted to remain stationary upon the mine floor, without tracks or braces or other holding or directing appliances, and is also adapted to travel about, forwardly or backwardly or angularly, or otherwise, upon the mine floor independently 35 of any track. The progressing means for the machine is arranged substantially parallel or in general alinement with the cutting movement of the cutting ring so that the machine may travel intermittently 40 across the exposed face of the vein, and at each pause the cutting ring may make one reciprocation and remove a bite from the face of the vein.

Referring more particularly to the 45 embodied construction of the means for supporting and moving the machine, there is provided a general carriage 110 upon which the entire machine is supported and carried. The carriage 110 comprises side beams 111 and 112, and the carriage is supported at either end by a caterpillar tread, the treads in the preferred form being arranged transversely to the length of the machine. As 50 embodied, the forward tread comprises a series of iron plates 113 provided with projecting studs or points 114. The plates 113 are arranged transversely on the alternate links of an endless sprocket chain 115. The 55 sprocket chain 115 of the forward tread, which tread is located adjacent to and pref-

erably just forward of the post 72, is carried over an idler sprocket wheel 116 and over a driven sprocket wheel 117. The sprocket wheel 117 is fixed on a shaft 118, extending backwardly along the carriage 70 110 (Figs. 3 and 4) to the rear caterpillar tread which is shown in Figs. 2, 4 and 6. The shaft 118 is journaled in the machine frame, and at its rear end is provided with a worm gear 119, which meshes with a worm 75 120. Worm 120 is fixed on a shaft 121 mounted at the rear of the machine (Figs. 4 and 6).

Means are provided by the invention for driving the shaft 118, and therefrom the forward caterpillar tread 117, in either direction, either uniformly with, or independently of, the rear caterpillar tread, later to be described. In the embodied form of such means, there are loose on the shaft 121 80 two mitre gears 122 and 123, which gears are in mesh with a mitre gear 125. Between the gears 122 and 123, on shaft 121, rotatable therewith but slidable therealong is a clutch member 124, adapted to engage either with a clutch member formed on the hub of gear 122 or with a clutch member formed on the hub of gear 123, to reverse the direction of drive of shafts 121 and 118 85 from motor 131, and thereby to drive the forward caterpillar tread in either direction.

Mitre gear 125 is fixed on a shaft 126, journaled in a bearing 127. Fixed on shaft 126 is a worm gear 128, driven from a worm 129, fixed on the shaft 130 of a motor 131. Mounted loosely on shaft 130 is a clutch for throwing in and out the motor 131 with respect to the worm 129, and as 90 embodied worm 129 is provided with a clutch member 132, a cooperating clutch member 133 being rotatable with and 95 slidably along the shaft 130. Worm 129 also drives the rear caterpillar tread, and clutch 132, 133 disconnects the motor from this also.

The rear caterpillar tread is preferably of 100 similar construction, and as shown comprises metal plates 140, provided with sharp points 141, the plates 140 being carried upon the sprocket chain 142. Sprocket chain 142 passes over an idle sprocket wheel 143, mounted in an extension of the machine frame, and passes also over a driven sprocket 105 wheel 144. Sprocket wheel 144 is fixed on a shaft 145, and fixed also on shaft 145 is a worm gear 146, with which intermeshes a worm 147. Worm 147 is fixed on a shaft 148, mounted at the rear of the machine, and 110 preferably in alinement with the shaft 121. Mounted loosely on shaft 148 are two mitre gears 149 and 150 in mesh with a driving mitre gear 151. Mounted on shaft 148, and 115 slidable therealong but rotatable therewith, is a clutch member 139, adapted to pass into 120 125 130

engagement either with a clutch member formed on the hub of gear 150 or with a clutch member formed on the hub of gear 151, to drive shafts 148 and 145, and therefore with the rear caterpillar tread in either direction. The actuating levers for clutches 124 and 139 are omitted for the sake of clearness. These may be, like other omitted clutch-actuating levers, of any usual or convenient form. Gear 151 is fixed on a shaft 154, to which shaft is fixed a worm gear 155. Worm gear 155 meshes with the worm 129 already described, that also drives worm gear 128 and shafts 121 and 118.

Through the clutch 132, 133 the entire drive for the caterpillar tread may be thrown out and the machine remain at rest. Either gear of the pair of driving gears 122, 123 and 149, 150 by their own clutches may be thrown into mesh with their respective driven shafts, or each of said pairs of gears may be thrown into a neutral position. Thus either caterpillar tread may be operated alone in either direction, or simultaneously with the other in either direction, or the treads may be operated in opposite directions at the same time to progress, maneuver and position the machine.

Means are provided for tilting the cutting ring to travel and cut at a variable angle upwardly or downwardly, and in the embodied form of such means, the bed 71 is made rotatable upon the carriage 110, thereby tilting the entire mechanism carried by the bed. In such embodied form, the bed 71 is formed with its lower portion 160 of semi-cylindrical shape, such portion having formed on the exterior thereof an arcuate series of teeth 161. Meshing with the teeth 161 is a worm 162, fixed on a shaft 163, which shaft is journaled in lugs 164 and 165 on the machine frame. The shaft 163 may be rotated in any suitable manner, and in the embodied form it is provided with a squared end 166, adapted to take a crank or bar so that the mechanism may be tilted in either direction by hand. Thus, the cutting ring as it moves forward through the vein may move in the general plane of the vein, or inclined upwardly or downwardly with respect thereto.

Means are provided for conveying the mineral backwardly from the cutting ring, and in accordance with certain aspects of the invention, cooperating therewith are means for conveying the dislodged mineral away and loading it upon the mine cars.

As embodied, there is fixed to the supporting ring 11 a cylindrical, arcuate pipe 170 which communicates with a similar pipe or semi-cylindrical member 171, the latter encircling the former so that they will telescope upon the application of end pressure. Located within and at the rear end of the section 171 are a series of teeth or blades 172, carried upon pivotal mountings 173,

the blades 172 being positioned to freely permit the passage of the broken and dislodged mineral in one direction, but preventing its passage in the opposite direction. Mounted in the upper, rear portion of the section 171, by pivotal supports 174 are a series of arms 175, carrying downwardly extending arms 176, provided with one or more arcuate blades 177. The purpose of the blades 172 and 177 is to convey the mineral rearwardly away from the cutting ring during the relative movement of the parts 170 and 171. As the telescoping action occurs, the mineral in the section 171 would tend to move into the section 170, but encountering blades 172, these are raised upwardly a short distance, and hold the mineral against moving forwardly into section 170, and thereby it is pushed out of or ejected from the rear end of section 171.

During the movements just described, the blades 177 have been pushed forward over the top of the coal in section 170, the arms 176 yielding during such movement. When the parts move in the opposite direction, the blades 177 engage with the mineral and gradually sink deeper and deeper into the mass of disengaged mineral in the section 170, and as the section 171 moves rearwardly, the coal from section 170 is drawn into the section 171. As the cutting ring moves forward to the work, the section 170 moves out from within the section 171 and the coal from the former is conveyed into the latter, leaving the section 170 vacant to receive the mineral which is to be cut from the vein by the cutting ring. As the cutting ring swings back for a new cut, section 170 passes within the section 171, and the mineral within the latter is pushed out upon the conveyor by the blades 172.

In conjunction with the foregoing, means are provided for loading the dislodged mineral into mine cars, and in accordance with certain features of the invention, the conveying and loading means are adapted to convey the mineral from the machine, while the latter is traveling or positioned to and fro across the exposed face of the vein, to a car standing upon a track. In Figs. 7 and 8 is shown (more or less diagrammatically) the embodied form of such means, an enlarged, fragmentary view of the conveyor being shown in Fig. 12.

As embodied, means are provided for raising and lowering the rear end of the conveyor member 171 in conformity with the raising and lowering of the cutting ring. As embodied near the rear end of the section 171 is an outwardly projecting bracket 180, having formed on the external face thereof a vertically disposed, undercut guiding member 181. This member slides vertically in a guide 182 formed in a bracket or frame member 183 extending outwardly from the

frame of the machine. Supported on the bracket 183 is a shaft 184 provided with a handle 185. The shaft 184 is in screw-threaded engagement with the vertically 5 slidable guide piece 181, and by turning the hand wheel 185 the guide piece 181 and the conveyor 171 are raised and lowered as desired.

Cooperating with the section 171 is a 10 receiving conveyor 186. The conveyor section 171 is provided with plates 187 and 188 at either side, shaped to direct and forward the mineral to the conveyor 186. The conveyor 186 may be of endless belt form, running over rollers 190 and 191. The roller 191 is driven in suitable manner, and as shown is driven by a sprocket wheel 192 fixed on the roller shaft. Running over the sprocket wheel 192 is a sprocket chain 193 20 which also runs over a sprocket gear 194 on the shaft of a driving motor 195. The motor 195 is mounted upon the frame 196 of the conveyor section.

The mineral is discharged from the conveyor section 186 to a conveyor 197, which conveyor has swiveled mountings at the end thereof to permit the mining machine to travel transversely or directly across the direction of the mine car track. As embodied, the conveyor 197 is likewise of endless belt form, and runs over rollers 198. One of said rollers is driven in a suitable manner, as by a sprocket wheel 199 on the shaft thereof. Over wheel 199 runs a sprocket chain 200, the latter running also over a sprocket pinion 201, on the shaft of a motor 202. The motor 202 is shown mounted on the longitudinal frame 203, of the conveyor, the motor being within the conveyor.

Means are provided for permitting a swiveling action between the two conveyors, and for this purpose (Figs. 12 and 13) the roller 191 is mounted in a frame 205, swiveled upon a frame 206, within which latter frame is journaled the driving roller 198. The various conveyors may be supported on wheels or may be carried as desired on the main machine frame. A suitable apron or shield 207 directs the coal from the conveyor 186 to the conveyor 197.

The conveyors are preferably and usually inclined upwardly to deliver the dislodged mineral over the top of the mine car.

The conveyor 197 at its rear or discharge 55 end is pivotally carried or supported upon a frame or carriage 210, which preferably runs upon wheels upon the mine track (Figs. 7 and 8). The conveyor 197 is provided at either side with guiding plates 211, 60 212 to convey the broken mineral forwardly along the conveyor. The carriage 210 is preferably supported upon wheels or trucks 213 and 214, resting upon the mine track 215. The rear or discharge end of the conveyor 197 is preferably provided with a

supporting frame (generally similar to the 70 frame 205 shown in Fig. 13), which frame is pivotally mounted at 218 on the carriage 210. A discharge chute 216 may be used to deliver the coal into a mine car 217. The machine thus moves to and fro transversely 75 across the exposed face of the vein, and the carriage 210 and the car 217 may be moved along the track 215, dependent upon changes in the position of the machine, as regards its approach to and recession from the track 80 215.

From all the foregoing, it will be understood that a machine has been provided embodying the features of the invention and the advantages herein described and indicated, together with other advantages which will be obvious to those skilled in the art, or which may be learned by practice with the invention. It will be further understood that the invention is not limited to the particular constructions herein shown and described, nor to any particular details of construction, but that changes may be made therefrom without departing from the principles of the invention and without sacrificing 90 its chief advantages.

What I claim as my invention is:—

1. A mining machine including in combination a rotating tubular cutter, power operated means for advancing the rotating cutter to cut the mineral from the vein, and power operated means for reversing the advancing means to return the cutter for a new bite on the vein.

2. A mining machine including in combination a rotating tubular cutter, power operated means for angularly advancing the rotating cutter to cut the mineral from the vein, and power operated means for reversing the advancing means to return the cutter 110 for a new bite on the vein.

3. A mining machine including in combination a rotating tubular cutter, power operated means for yieldingly advancing the rotating cutter to cut the mineral from the vein, and power operated means for reversing the advancing means to return the cutter 115 for a new bite on the vein.

4. A mining machine including in combination a rotating tubular cutter and an eccentric pivotal mounting therefor, power operated means for swinging said cutter about its mounting to cut the mineral from the vein, and power operated means for reversing the advancing means to return the cutter 120 for a new bite on the vein.

5. A mining machine including in combination a rotating tubular cutter and an eccentric pivotal mounting therefor, a motor and connections for swinging the cutter about its mounting to cut the mineral from the vein, and a reversing device in said connections to return the cutter for a new 130 bite on the vein.

6. A mining machine including in combination a ring cutter for cutting a solid core of mineral, and means for progressing the cutter through the mineral to remove it from the vein and for retrogressing the cutter for a new bite on the vein, said progressing and retrogressing means comprising a motor and connections therefrom to the cutter, including a reversing device. 5
- 10 7. A mining machine including in combination a rigid rotating ring for removing a core of mineral from the vein, an eccentric, pivotal mounting therefor, a motor and connections therefrom for swinging the ring about its pivotal mounting, said connections including a direction reversing device. 15
- 20 8. A mining machine including in combination a rigid rotating ring for removing a core of mineral from the vein, an eccentric, pivotal mounting therefor, a motor and yieldable connections therefrom for swinging the ring in either direction about its pivotal mounting. 25
- 25 9. A mining machine including in combination a rigid rotating ring for removing a core of mineral from the vein, means for raising and lowering the ring relatively to the vein, and a motor for rotating the ring 30 and for operating said raising and lowering means.
- 35 10. A mining machine including in combination a rigid rotating ring for removing a core of mineral from the vein, means for raising and lowering the ring relatively to the vein, and a motor for rotating the ring and for operating said raising and lowering means, connections from the motor to the ring including a clutch, and connections 40 from the motor to the raising and lowering means including a reversing clutch.
- 45 11. A mining machine including in combination a rigid rotating ring for removing a core of mineral from the vein, means for raising and lowering the ring relatively to the vein, and a motor for rotating the ring, and a flexible gear train between the motor and ring. 50
- 55 12. A mining machine including in combination a rigid rotating ring for removing a core of mineral from the vein, means for raising and lowering the ring relatively to the vein, and a motor for rotating the ring, and a flexible gear train and a clutch 60 between the motor and ring.
- 65 13. A mining machine including in combination a support and vertical guides thereon, a cutting ring for cutting out a core of mineral, a supporting frame therefor 60
- 70 14. A mining machine including in combination a support and vertical guides thereon, a cutting ring for cutting out a core of mineral, a supporting frame therefor 75
- 75 15. A mining machine including in combination a support and vertical guides thereon, a cutting ring for cutting out a core of mineral, a supporting frame therefor 80
- 80 16. A mining machine including in combination a support and vertical guides thereon, a cutting ring for cutting out a core of mineral, a supporting frame therefor 85
- 85 17. A mining machine including in combination a carriage, a platform pivotally mounted thereon, a cutting ring carried by said platform, a motor on said platform and connections between the motor and carriage 90
- 90 18. A mining machine including in combination a carriage, a platform pivotally mounted thereon, a cutting ring carried by said platform, a motor on said platform and connections between the motor and carriage 95
- 95 19. A mining machine including in combination a carriage, a platform pivotally mounted thereon, a cutting ring carried by said platform, a motor on said platform and connections, including a yielding driving device, between the motor and carriage for 100
- 100 20. A mining machine including in combination a carriage, a platform pivotally mounted thereon, a cutting ring for cutting out a core of mineral carried by said platform, a motor on said platform and connections between the motor and carriage for 110
- 110 21. A mining machine including in combination a carriage, a platform pivotally mounted thereon, a cutting ring carried by, but vertically movable relatively to, said 115
- 115 22. A mining machine including in combination a carriage, a platform pivotally mounted thereon, a cutting ring carried by, but vertically movable relatively to, said 120
- 120 23. A mining machine including in combination a carriage, a platform pivotally mounted thereon, a cutting ring carried by, but vertically movable relatively to, said 125
- 125 24. A mining machine including in combination a carriage, a platform pivotally mounted thereon, a cutting ring carried by, but vertically movable relatively to, said 130

raising and lowering the ring relatively to the vein, and connections between the motor and carriage for swinging the platform and ring about the pivotal mounting.

5 23. A mining machine including in combination a carriage, a rotatable cutting ring mounted thereon for cutting out a solid core of mineral, means for advancing the ring relatively to the carriage, a motor on the carriage, and means driven by the motor for steering and advancing the carriage over the mine floor.

10 24. A mining machine including in combination a carriage, a rotatable cutting ring mounted thereon for cutting out a solid core of mineral, means for advancing the ring relatively to the carriage, a motor on the carriage, and carriage traveling and steering means comprising a plurality of carriage supporting and progressing members resting on the mine bottom and driven by the motor.

15 25. A mining machine including in combination a carriage, a rotatable cutting ring mounted thereon, means for advancing the ring relatively to the carriage, a motor on the carriage, and carriage traveling means comprising a plurality of carriage supporting and progressing members resting on the mine bottom and driven independently as to direction to impart rectilinear or angular movement to the carriage by the motor.

20 26. A mining machine including in combination a carriage, a rotatable cutting ring mounted thereon, power operated means for angularly advancing the ring relatively to the carriage, a motor on the carriage, and means driven by the motor for advancing the carriage over the mine floor.

25 27. A mining machine including in combination a carriage, a rotatable cutting ring mounted thereon, power operated means for angularly advancing the ring relatively to the carriage, a motor on the carriage, and carriage traveling means comprising a plurality of endless traction treads resting on the mine bottom and driven independently as to direction to impart rectilinear or angular movement to the carriage.

30 28. A mining machine including in combination a carriage, a rotatable cutting ring mounted thereon, power operated means for advancing the ring relatively to the carriage, a motor on the carriage, and carriage traveling means comprising a plurality of carriage supporting and progressing members resting on the mine bottom, driving connections therefrom to the motor including a clutch for each of the carriage supporting and progressing members.

35 29. A mining machine including in combination a carriage, a rotatable cutting ring mounted thereon, power operated means for advancing the ring relatively to the carriage, a motor on the carriage, and carriage

traveling means comprising a plurality of endless traction treads resting on the mine bottom, driving connections therefrom to the motor including a reversible clutch for each of the carriage supporting and progressing members.

70 30. A mining machine including in combination a carriage, a platform pivotally mounted thereon, a cutting ring carried by said platform, a motor on said platform and connections between the motor and carriage for swinging the platform and ring about the pivot, and carriage progressing means comprising a plurality of separately movable members resting on the mine bottom.

75 31. A mining machine including in combination a carriage, a platform pivotally mounted thereon, a cutting ring carried by said platform, a motor on said platform and connections between the motor and carriage for swinging the platform and ring about the pivot, and carriage progressing means comprising a plurality of separately movable members resting on the mine bottom, said carriage progressing members being movable independently as to direction to impart either rectilinear or angular movement to the carriage.

80 32. A mining machine including in combination a carriage, a platform pivotally mounted thereon, a cutting ring carried by said platform, means for swinging the platform and ring about the pivot, and carriage progressing means comprising a plurality of separately movable members resting on the mine bottom.

85 33. A mining machine including in combination a carriage, a platform pivotally mounted thereon, a cutting ring carried by said platform, means for swinging the platform and ring about the pivot, and carriage progressing means comprising endless traction treads resting on the mine bottom, said endless traction treads being movable independently as to direction to impart either rectilinear or angular movement to the carriage.

90 34. A mining machine including in combination a carriage, a platform pivotally mounted thereon, a cutting ring carried by said platform, a motor on said platform and connections between the motor and carriage for swinging the platform and ring about the pivot, a motor on said carriage, and a pair of caterpillar treads driven thereby.

95 35. A mining machine including in combination a carriage, a platform pivotally mounted thereon, a cutting ring carried by said platform, a motor on said platform and connections between the motor and carriage for swinging the platform and ring about the pivot, a motor on said carriage, and a pair of caterpillar treads driven thereby and a reversible clutch between each tread and the motor.

36. A mining machine adapted to travel transversely across the exposed face of the vein including in combination a rotating ring cutter for cutting out a core of mineral, 5 a conveyor for conveying the dislodged mineral away from the machine, and a support whereon the conveyor is angularly mounted, said support being adjacent to a receiving car on the mine track.

10 37. A mining machine adapted to travel transversely across the exposed face of the vein including in combination a rotating ring cutter for cutting out a core of mineral, a conveyor for conveying the dislodged 15 mineral away from the machine, and a support whereon the conveyor is angularly mounted, said support being mounted on the mine track adjacent to a receiving car.

20 38. A mining machine including in combination a cutting device advancing through the vein to dislodge the mineral, a receptacle receiving the dislodged mineral, said receptacle comprising two cooperating telescoping sections, and a conveyor carrying 25 the mineral from the receptacle to a receiving car.

30 39. A mining machine including in combination a cutting device advancing through the vein to dislodge the mineral, a receptacle receiving the dislodged mineral, said receptacle comprising two cooperating telescoping sections, devices effecting a forward movement of the mineral from one section to another, and a conveyor carrying the mineral 35 from the receptacle to a receiving car.

40 40. A machine of the class specified comprising a tubular receiver provided with an inlet at one end and a movable cutter at said open end of the receiver and through which the cut material also passes, and a support for the receiver having a swinging movement in the arc of a circle and also adjustable vertically, the receiver having an outer curved side corresponding in degree of curvature to the arc through which the receiver and support have swinging movement.

45 41. A machine of the class specified comprising a tubular receiver provided with an inlet at one end and a movable cutter and a frame therefor at said inlet end of the receiver and through which the cut material also passes, and a support for the receiver having a swinging movement in the arc of a circle and also adjustable vertically, the receiver having an outer curved side corresponding in degree of curvature to the arc through which the receiver and support have swinging movement and the cutter frame also having an outer curved surface which is 50 a continuation of the same arc as the outer side of the receiver.

55 42. A machine of the class specified comprising a tubular receiver having cutting means operating therewith, and conveying means also associated with the receiver, the

cut material collecting in bulk charges in the receiver and the successive charges of bulk material entering the receiver forcing out the preceding charges therefrom to the conveying means.

70 43. A machine of the class specified comprising a tubular receiver having an inlet opening at one end and a cutting means movable around the said end, the cut material being free to pass through the cutting means 75 into the receiver, a support for said receiver, the said support being operable to swing in the arc of a circle and also adjustable to different elevations, and mechanism independently operable for controlling the swinging 80 movement of the support and receiver and the variation in elevation thereof.

85 44. A machine of the class specified having a tubular receiver with a cutting component at one end forming a part thereof, the receiver and its cutting component being mounted to swing as a unit in an arcuate path and simultaneously operable for cutting and gathering up and carrying material from the face of a vein or ledge in the 90 direction of movement of the said receiver and cutting component, the cut material being passed directly into and carried by the receiver during the cutting operation, the discharge of the cut material from the receiver being effected by the successive charges of material passed thereinto.

95 45. A coal cutting machine comprising a swinging enclosure which directly receives and carries the coal as it is cut, the enclosure 100 having an open cutting component rotatably mounted on one end and forming a part thereof to cut the coal in columns from the face of a vein and effect an immediate passing of each column into the enclosure, the 105 enclosure and its cutting component holding and carrying the columnar charge clear of the vein.

110 46. A mining machine including in combination a frame, a tubular cutter pivoted to the frame, for cutting out a core of mineral, and power operated means for swinging the cutter about its pivot in one direction for progressing the cutter through the vein, and for swinging it in the reverse direction for 115 a new bite on the vein.

115 47. A mining machine including in combination a frame, a tubular cutter ring, pivoted to the frame, for cutting out a core of mineral, a motor carried on the frame, 120 connections from the motor for rotating the cutting ring, and reversible connections from the motor for swinging the cutter above its pivot.

125 48. A mining machine including in combination a machine frame, a ring cutter for cutting out a core of mineral, a frame for the cutter pivoted to the machine frame, means for swinging the cutter frame about its pivot, endless traction treads alongside 130

the machine, and means for driving the treads independently or together.

49. A mining machine including in combination a machine frame, a rotating ring cutter for cutting out a core of mineral, a frame for the cutter pivoted to the machine frame, power operated means for swinging the cutter and cutter frame about its pivot, endless traction treads alongside the machine, and means for driving the traction treads independently or together.

50. A mining machine including in combination a machine frame, a ring cutter for cutting out a core of mineral, a frame for the cutter movable up and down to successively parallel operative positions, endless traction treads alongside the machine frame, and means for driving the treads independently or together.

51. A mining machine including in combination a machine frame, a ring cutter for cutting out a core of mineral, a frame for the cutter pivoted to the machine frame and movable up and down thereon to successively parallel operative positions, endless traction treads alongside the machine frame, and means for driving the treads independently or together.

52. A mining machine including in combination a machine frame, a ring cutter for cutting out a core of mineral, a frame for the cutter, pivoted to the machine frame and movable up and down thereon to successively parallel operative positions, power operated means for swinging the cutter frame about its pivot, endless traction treads alongside the machine frame, and means for driving the treads independently or together.

53. A mining machine including in combination a frame, a ring cutter for cutting out a core of mineral, means for moving the cutter up and down to successively parallel operating positions, means for rotating the cutter, and means for forcing the cutter into the vein.

54. A mining machine including in combination a machine frame, a ring cutter for cutting out a core of mineral, a frame for the cutter pivoted to the machine frame, power operated means for swinging the cutter frame about its pivot, and means for

moving the cutter frame up and down to position the cutter in successively parallel operating positions.

55. A mining machine including in combination a frame, a ring cutter for cutting out a core of mineral, means for variably positioning the cutter at different levels such that the successive positions of the elements of the cutter are respectively parallel, a motor, and driving connections from the motor for rotating the cutter, and for moving the cutter to different operating levels.

56. A mining machine including in combination a machine frame, a ring cutter for cutting out a core of mineral, a frame for the cutter pivoted to the machine frame and movable up and down to successively parallel operating positions, a motor, connections from the motor for moving the cutter frame about its pivot, and connections from the motor for moving the cutter frame up and down.

57. A mining machine including in combination a machine frame, a ring cutter for cutting out a core of mineral, a frame for the cutter pivoted to the machine frame and movable up and down to successively parallel operating positions, a motor, connections from the motor for driving the cutter, for moving the cutter frame about its pivot, and for raising and lowering the cutter frame.

58. A mining machine including in combination a machine frame, a ring cutter for taking out a core of mineral, a frame for the cutter movable about vertical and horizontal axes, and also movable up and down to successively parallel operative positions, and means for driving the cutter.

59. A mining machine including in combination a machine frame, a ring cutter for taking out a core of mineral, a frame for the cutter movable about vertical and horizontal axes and also movable up and down to successively parallel operative positions, power operated means for moving the cutter frame about its vertical axis, and means for driving the cutter.

In testimony whereof, I have signed my name to this specification.

KENNETH DAVIS.
